UNITED STATES PATENT OFFICE

JOHN A. NAZ, OF GROSSE POINTE PARK, MICHIGAN

DESIGN FOR A WALL-LIGHT SCREEN OR SIMILAR ARTICLE

Application filed October 3, 1930. Serial No. 37,122. Term of patent 7 years.

To all whom it may concern:

Be it known that I, JOHN A. NAZ, a citizen of the United States, residing at Grosse Pointe Park, in the county of Wayne and State of Michigan, have invented a new, original, and ornamental Design for Wall-Light Screen or Similar Article, of which the following is a specification, reference being had to the accompanying drawing, forming part thereof.

Figure 1 is a front elevation of a screen

or similar article, showing my new design, and

Figure 2 is a vertical longitudinal section thereof.

The device consists of a face grid or screen 1 backed by a transparent sheet 2.

I claim:

The ornamental design for a wall light screen or similar article, as shown and described.

JOHN A. NAZ.
